Primary Examiner — Jennifer L Watkins

(57) **CLAIM**

The ornamental design for a shoe, as shown and described.

DESCRIPTION

1. Shoe

1.1 is a perspective view of a shoe showing a new design;

1.2 is a front view thereof;

1.3 is a rear view thereof;

1.4 is a side view thereof;

1.5 is an opposite side view thereof;

1.6 is a top view thereof; and

1.7 is a bottom view thereof.

The various views of the design show only the right shoe; the left shoe is not shown as it is symmetrical to the right one.
